(57) **CLAIM**

The ornamental design for a tire tread, as shown and described.

DESCRIPTION

FIG. 1 is a perspective view of the tire tread showing our design;

FIG. 2 is a left view thereof;

FIG. 3 is a right view thereof;

FIG. 4 is a front view thereof;

FIG. 5 is a rear view thereof;

FIG. 6 is a plan view thereof showing the tread pattern;

FIG. 7 is a plan view thereof showing the tread pattern, with section line A-A; and,

FIG. 8 is a sectional view taken along line A-A in FIG. 7. The broken lines are used to show portions of the tire tread that are not being claimed, and thus form no part of the claimed design.

1 Claim, 8 Drawing Sheets
